(57) **CLAIM**

The ornamental design for a curable liquid reservoir, as shown and described.

DESCRIPTION

FIG. 1 is a perspective view of the invention illustrated as a curable liquid reservoir;

FIG. 2 is a front view of FIG. 1, the rear, top and bottom views being identical to the front view;

FIG. 3 is a left side view of FIG. 1; and,

FIG. 4 is a right side view of FIG. 1.

The elements shown in dash-dot lines form no part of the claimed invention, and are instead included to show environmental aspects of the claimed invention.
